UNITED STATES PATENT OFFICE.

DELAVERGNE P. WILLIAMS AND JOHN F. WILLIAMS, OF NEW YORK, N. Y.

RELAY.

1,236,128.

Specification of Letters Patent.

Patented Aug. 7, 1917.

Application filed January 25, 1917. Serial No. 144,432.

To all whom it may concern:

Be it known that we, DELAVERGNE P. WILLIAMS and JOHN F. WILLIAMS, citizens of the United States, and residents of the city of New York, borough of Manhattan, in the county and State of New York, have invented a new and Improved Relay of which the following is a full, clear, and exact description.

10 This invention relates to electric relays for setting up in one circuit electric impulses derived through another circuit.

The invention has for its general objects to improve the construction and operation 15 of devices of this character so as to be reliable and efficient in use, comparatively simple and inexpensive to manufacture, and so designed as to possess a maximum sensitivity.

20 A more specific object of the invention is the provision of a novel form of diaphragm and means for mounting the same whereby the diaphragm is undamped as its peripheral edge is supported free, as distinguished 25 from those diaphragms which are clamped entirely around their peripheral edge in the body of a receiver or transmitter.

Another object of the invention is the provision of a novel arrangement of energizing 30 electromagnetic means and microphonic means for obtaining a maximum conversion of electric impulses in one circuit derived from another circuit.

With such objects in view, and others 35 which will appear as the description proceeds, the invention comprises various novel features of construction and arrangement of parts which will be set forth with particularity in the following description, and 40 claims appended hereto.

In the accompanying drawings, which illustrate certain embodiments of the invention and wherein similar characters of reference indicate corresponding parts in all the 45 views,

Figure 1 is a bottom plan view of the relay with the bottom of the casing removed;

Fig. 2 is a vertical section on the line 2—2, Fig. 1;

50 Fig. 3 is a diagrammatic view of circuit connections illustrative of one use of the relay;

Fig. 4 is a detail sectional view of one of the microphones;

55 Fig. 5 is a vertical sectional view of a modified form of relay;

Fig. 6 is a sectional view of another modified form; and

Fig. 7 is a plan view of the diaphragm element shown in Fig. 6.

Referring to the drawing, A designates a case of any suitable construction in which is mounted a vibratory element or diaphragm 1 that is set into vibration by electromagnets 2 and 3 disposed respectively above and below the diaphragm and at opposite sides of the center thereof, these electromagnets being adjustably mounted on horizontal brackets 4 and 5 fastened within the casing. The diaphragm is supported at diametrically opposite points and adjacent the periphery by microphones 7 and 8 which are respectively mounted on the brackets 4 and 5. The current impulses in the energizing circuit in which the electromagnets are included set up vibrations in the undamped diaphragm 1, which vibrations are communicated to the microphones that in turn cause current impulses to flow through the circuit or circuits in which they are connected.

A simple circuit arrangement is shown in Fig. 3, wherein the electromagnets 2 and 3 are connected in series with a source of current 9 and a transmitter 10. The microphones 7 and 8 are in series with each other 35 and with a battery 11 and receiver 12. The sounds to which the diaphragm of the transmitter 10 is exposed set up current impulses in the magnets 2 and 3 which vibrate the diaphragm 1, and this vibration varies the electrical resistance through the microphones and causes current impulses to be sent through the receiver 12. As the diaphragm is supported only at two points it is free to respond to the slightest magnetic influences 95 of the electromagnets, and these effects will be multiplied in the energizing circuit which contains the microphones and receiver. The microphones are insulated from their supporting brackets and diaphragm and the opposite terminal members 13 and 14 thereof are connected in the receiver circuit.

In the modification shown in Fig. 5 the diaphragm element 1^a is a strip of metal bent approximately into the form of an S, 105 and the ends 15 and 16 are clamped to the yokes or brackets 17 and 18 by the same means which fasten the magnets 19 and 20. The microphones 21 and 22 are connected adjacent the middle of the vibratory element 1^a, and the electromagnets act theron 110 at points outwardly from the microphones.

In the construction shown in Figs. 6 and 7 the diaphragm 1^b is an approximately rectangular plate which has slots 23 and 24 at its ends for adjustable connection with the microphones 25 and 26, which are shown on the same side of the diaphragm element. One or more electromagnets 27 are disposed in magnetic relation to the diaphragm element 1^b, and like the microphones it is adjustably mounted on the yoke or supporting frames 28.

From the foregoing description taken in connection with the accompanying drawings, the advantages of the construction and method of operation will be readily understood by those skilled in the art to which the invention appertains, and while we have described the principle of operation, together with the device which we now consider to be the best embodiment thereof, we desire to have it understood that the device shown is merely illustrative and that such changes may be made when desired as fall within the scope of the appended claims.

Having thus described our invention, we claim as new and desire to secure by Letters Patent:

1. A device of the class described comprising a diaphragm element, a plurality of microphones mechanically connected therewith, with the marginal portion of the element unsupported and free, and electromagnetic means for setting the diaphragm into vibration.

2. A relay comprising a diaphragm element supported at widely spaced points and having the major portion of its margin unsupported and free to vibrate, microphonic means operatively related to the diaphragm to be acted on thereby, and electromagnetic means for setting the diaphragm element into vibration.

3. A relay comprising a diaphragm, a plurality of microphonic means mechanically connected with and supporting the diaphragm, a circuit in which the said means are connected in series, an electromagnetic means for setting the diaphragm into vibration, and an energizing circuit in which the electromagnet is included. 45 50

4. A relay comprising a diaphragm, a plurality of microphonic means mechanically connected with and supporting the diaphragm, a circuit in which the said means are connected in series, an electromagnetic means for setting the diaphragm into vibration, and an energizing circuit in which the electromagnet is included, said electromagnet and microphonic means being relatively 55 60 adjustable.

5. The combination of an undamped diaphragm, a plurality of microphones connected therewith at opposite sides of the center, and a plurality of electromagnets acting on the diaphragm at opposite sides of the center. 65

6. The combination of an undamped diaphragm, a plurality of microphones connected therewith at opposite sides of the center, a plurality of electromagnets acting on the diaphragm at opposite sides of the center, and means on which the microphones and electromagnets are adjustably mounted. 70

7. The combination of an undamped diaphragm, a plurality of microphones connected therewith at opposite sides of the center, a plurality of electromagnets acting on the diaphragm at opposite sides of the center, a receiver circuit in which the microphones are connected in series, and a transmitter circuit in which the electromagnets are connected in series. 75 80
